CLAIM

The ornamental design for spectacle front, as shown and described.

DESCRIPTION

FIG. 1 is a front elevational view of glasses simulating the eyes and antennae of an insect, showing my new design;

FIG. 2 is a rear elevational view thereof;

FIG. 3 is a side elevational view thereof taken from the right in FIG. 1 with the parts shown in broken lines being for illustrative purposes only;

FIG. 4 is a top plan view thereof taken from above in FIG. 3 with the parts shown in broken lines being for illustrative purposes only; and

FIG. 5 is a bottom plan view with the parts shown in broken lines being for illustrative purposes only.

FIG 1

FIG 2

FIG 5
